DESIGN FOR A PORTABLE COMBINED SEAT AND BACK REST

Joseph Archer, Chicago, Ill.

Application October 11, 1939, Serial No. 87,620

Term of patent 3½ years

To all whom it may concern:

Be it known that I, Joseph Archer, a citizen of the United States, residing at Chicago, in the county of Cook and State of Illinois, have invented a new, original, and ornamental Design for a Portable Combined Seat and Back Rest, of which the following is a specification, reference being had to the accompanying drawing, forming a part thereof.

Figure 1 of the drawing is a perspective view of a portable combined seat and back rest embodying my new design; and

I claim:

The ornamental design for a portable combined seat and back rest, substantially as shown.

JOSEPH ARCHER.
